UNITED STATES PATENT OFFICE.

REINHOLD A. NORLING, OF AURORA, ILLINOIS, ASSIGNOR TO INDEPENDENT PNEUMATIC TOOL COMPANY, OF CHICAGO, ILLINOIS, A CORPORATION OF DELAWARE.

PNEUMATIC MOTOR.

Original application filed August 11, 1919, Serial No. 316,794. Divided and this application filed November 3, 1921. Serial No. 512,503.

This invention relates to piston actuated pneumatic motors for portable power hoists and other devices requiring motors of such kind.

5 One object of my invention is to provide an improved form of means for shifting the eccentric of the motor for changing the action of the valves to reverse the operation of the motor.

10 Another object of my invention is to effect the shifting of the eccentric before the starting valve of the motor is opened and thus prevent starting the motor before the eccentric is completely shifted.

15 A further object of my invention is to connect the eccentric shifting and starting valve opening mechanisms together, so that the reversing of the motor and the starting and stopping of the same may be accomplished by actuating but one member.

20 A still further object of my invention is to locate this operating member outside of the motor and readily accessible to the grasp of the operator so that the motor may be reversed whenever and as often as desired.

The invention consists further in the matters hereinafter described and more particularly set forth in the appended claims.

In the accompanying drawings—

25 Fig. 1 is a front elevational view of a portable power hoist having a pneumatic motor embodying the features of my invention;

Fig. 2 is an enlarged vertical sectional view taken on line 2—2 of Fig. 1;

Fig. 3 is a transverse vertical sectional view taken on line 3—3 of Fig. 2;

Fig. 4 is a horizontal sectional view taken on line 4—4 of Fig. 2;

40 Fig. 5 is a vertical sectional view taken on line 5—5 of Fig. 4;

Figs. 6 and 7 are top plan and side elevational views, respectively, of the eccentric shifter, to be described;

45 Fig. 8 is a perspective view of the rack operated by said shifter;

Fig. 9 is a longitudinal sectional view of the hollow shaft in which the eccentric shifter is mounted; and

50 Fig. 10 is a perspective view of the eccentric.

The starting valve operating and the motor reversing mechanisms of my invention are shown herein as applied to a pneumatic motor, such as is used with the portable

hoist described and claimed in my Patent No. 1,459,032 granted June 19, 1923, and of which the present application is a division.

As illustrated herein, the hoist comprises, in general, a hollow casing 1, two drums 2, 2, 60 rotatably mounted on a stationary shaft 3 in said casing. Each drum has a continuous spiral groove extending about the same to receive a rope or cable 4. A single cable is employed, with a portion wrapped in a 65 single layer about each drum, the loop at the mid-portion of the cable being outside of the casing 1 and trained about a grooved pulley or sheave 5 journaled in a frame 6 carrying a swivel hoisting hook 7, as shown 70 in Fig. 1; the casing having an elongated opening extending across its front to permit the cable to extend outside of the same. Extending between the opposed ends of the drums 2, 2 is a main power shaft 8 having a 75 worm 9 in mesh with a worm gear 10, keyed or otherwise fixed to a shaft 11 journaled in the casing below the shaft 8, as shown in Fig. 2. The shaft 8 is supported at its ends in the casing by anti-friction bearings 12, 13, 80 so made and arranged that by removing a screw 14 the shaft 8 may be pulled endwise out of the casing after the motor, to be hereinafter described, has been removed. The shaft 11 is provided on opposite sides of the 85 worm gear 10 with gear teeth 15 in mesh with gear teeth 16 on the drums 2, 2, so that the drums will be rotated in unison and at the same rate of speed and in the same direction for winding the cable on and unwind- 90 ing it from the same.

Secured to the outside of the hoist casing 1 is a pneumatic motor having a crank case 17, which has a crank case cover 18. The motor has double acting pistons in cylinders 95 19, 19 in the same plane and arranged V-shaped, as shown in Figs. 1 and 3. The crank shaft consists of a crank pin 20, formed integral with a counter-weight 21 on the worm shaft 8, this shaft extending into 100 the crank case through the front of the drum casing and supported by a plate 22 carrying the bearing 13 and secured to the drum casing by screws 23. The pistons in the cylinders are connected with the crank pin 20 105 by connecting rods 24, 25, as shown.

The crank case cover 18 is provided with an outwardly extending tubular portion 26 aligned with the worm shaft 8. In this extension is mounted a hollow shaft 27 hav- 110

ing at its inner end a disc 28 located in the crank case 17 and provided with a flat-sided peripheral slot 29 to receive the flattened end 30 of the crank pin 20, thus providing 5 a removable connection between these parts. The shaft 27 is supported in the crank case cover 18 by a bushing 31. Said shaft 27 is provided with an annular shoulder 32 bearing against a shoulder 33 on the extension 10 26 to hold the shaft from endwise movement in that direction, movement of the shaft 27 in the opposite direction being prevented by the disc 28 engaging against the flat shoulders at the end of the crank pin 20.

15 Applied about the shaft 27 between the cover 18 and disc 28 is an eccentric 34 surrounded by two eccentric straps 35, 36 arranged side by side and connected with valve rods 37, 37, which have pivotal connection 20 at their upper ends with piston valves 38 in the valve cylinders, as shown in Fig. 3, to control the admission and exhaust of motive fluid to and from the power cylinders 19. The eccentric has an internal diameter 25 greater than the shaft 27, while its outer diameter is made eccentric to the internal diameter thereof, as shown in Fig. 10. The eccentric is shifted for setting the valves 38 to reverse the operation of the motor.

30 When the eccentric 34 is shifted to one position, the valves 38 will operate to cause the motor to run forward and wind the cable on the drums, and when shifted to the opposite position will cause the motor to run 35 in the reverse direction and unwind the cable from the drums. To shift the eccentric for this purpose, I provide the following construction.

40 Slidably mounted in the hollow shaft 27 is an eccentric shifter 39 having its inner end bifurcated, as at 40 (Fig. 6), and with its bifurcated portions provided with rack teeth 41, meshing with a pinion 42 extending transversely through the hollow shaft 27 and 45 having its inner ends received in circular sockets or holes 43, 43 formed in the shaft, as shown in Fig. 9. The ends of said pinion 42 bear against the bushing 31, as shown in Fig. 5, and thus hold the pinion from endwise displacement, while permitting it to be rotated by the rack teeth 41 upon endwise movement being given to the shifter 39. Extending transversely through the hollow shaft 27 beyond the pinion 42 is a block 44 having rack teeth 45, as shown in Figs. 4 50 and 8, and in mesh with the pinion 42 arranged at right-angles to the shifter 39. This block 44 extends through the slot 40 at the end of the shifter and has its ends 55 projecting diametrically beyond the shaft 27 through slots 46 provided for that purpose. The block 44 extends across the inside of the eccentric, thereby connecting the eccentric 60 to the block and holding such parts

from rotation with respect to each other, while at the same time having the block support the eccentric about the shaft 27. Thus, when the shifter 39 is moved endwise, the block 44 is moved across the shaft 27 and 70 the eccentric 34 shifted with respect to the shaft 27 for the purpose of changing the eccentricity of such parts to set the valves 38 for the purposes stated.

75 For moving the shifter 39 from the exterior of the motor, I provide on the outside thereof a control lever 48, having the shape shown in Fig. 1 and provided at its center with a hub 49, from which extend arms 50, 51. These are provided with depending 80 chains 52, 53, each provided with a handle, as shown in Fig. 1. By pulling down on the chain 52, the motor will run forward and wind the cable on the drums, whereas by pulling down on the chain 53 the motor 85 will run reverse and unwind the cable from the drums. To effect this, the control lever 48 is connected with the shifter 39 by the following construction, which causes endwise movement to be given to the shifter 39 90 upon the actuation of said control lever.

95 The hub 49 of said control lever 48 is rotatably mounted on the extension 26, there being a bushing 54 inserted between such parts, as shown in Figs. 4 and 5. The bushing and hub are connected together so as to turn in unison, this being accomplished by providing such parts at their inner ends with lugs or flanges 55, 56 (Fig. 4) connected together by screws 57. The hub 49 100 extends beyond the outer end of the extension 26 to provide a space into which extends the outer end of the shifter 39. The outer end of this part, as shown in Figs. 6 and 7, is reduced in diameter to provide an annular 105 shoulder 58. Mounted on such portion of the shifter is a disc 59 bearing against the outer end of the bushing 54. The other side of said disc 59 bears against a shoulder 60 formed on the hub 49, as shown in Figs. 4 110 and 5. By this construction the disc 59 is clamped between the hub 49 and the bushing 54 and moved endwise with such parts in the shifting of the member 39.

115 On opposite sides of the disc 59 are key washers 61, 62 connected with the shifter 39 through a key slot 64, as shown. The extreme outer end portion 65 of the shifter 39 is further reduced to provide an annular shoulder 66, against which the outermost 120 washer 62 bears to prevent the same from being forced against the intermediate one 59 and pinching or clamping the same between the washers 61, 62. This end 65 of the shifter is threaded to receive a clamp nut 67, 125 which holds the washers in place, and the outer end of the hub 49 is threaded to receive a hub cap 68 to cover the parts.

130 A pin or stud 69 is fixed or screwed into the extension 26 and projects into a slot 70

formed in the bushing 54. This slot is milled spiral in the center and straight at its ends, so that upon the rotation of the hub 49, the shifter 39 will be moved endwise as the stud 5 is in the spiral portion of the slot 70 and thus effect shifting of the eccentric 34 for reversing the motor. The ends of the slot are straight in order that the hub 49 may have a partial rotation without moving the 10 shifter 39 endwise and thus permit the shifting of the eccentric to be accomplished before the starting valve of the motor is opened and the motor started.

The starting valve is constructed as follows. As shown in Fig. 3, the piston valves 38 are reciprocated in cylinders 71, 71, arranged V-shaped, as are the power cylinders 19. Each cylinder 71 is provided with a port 72 communicating with pipes 73, 73 15 coupled together at their meeting ends by a coupling 74. One of the pipes 73 is provided with a tubular extension 75, arranged substantially at right-angles thereto, and screwed into the open end of this extension 20 25 is a plug 76, carrying a nipple 77, to which is connected an air supply hose or pipe (not shown). The plug 76 is provided at its inner end with a wall having air passages which open into a chamber 78 formed in the 30 extension 75. This chamber communicates with a chamber 79 through a port 80, which is normally closed by a valve 81. Said valve has a stem 82 slidably mounted at its inner 35 end in the plug 76 and at its outer end in the casing 75 and is there provided with an outwardly projecting part 83.

For opening the valve 81, I provide a trigger 84 pivoted between ears 85 and having a depending plug 86 to operate against the outer end 83 of the valve stem 82 for moving the valve into open position to permit motive fluid to enter the chamber 79 and thence flow into the power cylinders through the pipes 73, 73 and ports of the valve cylinders, as usual in motors of this character. The valve 81 is normally held closed by a spring 87, and the trigger 84 is normally held in position out of engagement with the valve stem 82 by a spring 88, one end connected with a fixed lug 89 on the valve casing and the other end connected with the trigger, as shown in Fig. 2.

The lower arm 90 of the trigger 84 is provided at its outer end with a ball 91 retained 55 in a socket 92 at the upper end of a vertically arranged rod 93, which extends toward the hub 49. The lower end of this rod engages a ball 95 at the inner end of a bolt 96 clamped in an upright lug 97 fixed on the hub 49, as shown in Figs. 1 and 2. The spring 88 is strong enough, not only to maintain the trigger 84 in the normal position shown in Fig. 2, but also to hold the rod 93 in a vertical position and thus maintain the 60 65 control lever 48 in its neutral position, as

shown in full lines in Fig. 1. When either end of the lever 48 is pulled downward by the operator grasping either one of the handles at the ends of the chains 52, 53, the hub 49 is partially rotated, carrying therewith the fixed lug 97 and causing a downward pull to be exerted on the rod 93, which operates the trigger for opening the valve 81 and starts the motor. When the parts are thus moved, the rod 93 assumes position at 70 75 an angle to the vertical, the spring 88 always tending to restore the rod and control lever 48 to their normal or neutral positions so that when the operator releases his hold on the handle grasped by him, said spring 88 80 will act to restore the parts to their normal positions and stop the motor by cutting off the supply of live air thereto.

The drum casing 1 is provided with a swivel hook 98, as shown in Fig. 1, for suspending the hoist from an overhead support. The crank case cover 18 is secured to the body of the case by bolts 99, and the crank case is provided with a screw-plug 100, which when removed permits the same 90 to be drained of oil, the case also having an oil sight 101 to determine the level of the oil in the case, as shown in Figs. 1 and 3.

While I have shown and described herein the starting and reversing mechanisms of 95 my invention applied to a pneumatic motor for a portable power hoist, it is to be of course understood that the invention could be employed in pneumatic motors used for other purposes, and I do not wish to be 100 limited to the application of my invention to motors for the particular purpose disclosed, nor do I wish to be restricted to the details of construction and arrangement of parts illustrated, as such may be variously 105 changed and modified without departing from the spirit and scope of my invention.

I claim as my invention:

1. In combination in a fluid actuated motor, reciprocating valves for controlling the 110 admission and exhaust of motive fluid to and from the power cylinders of said motor, a hollow shaft, an eccentric surrounding said shaft and rotated thereby, said eccentric being connected with said valves for 115 operating the same, an eccentric shifter slidably mounted in said hollow shaft and having rack teeth, a gear pinion mounted in said hollow shaft and in mesh with said rack teeth, a block extending across said 120 shaft and supporting said eccentric and having rack teeth in mesh with said pinion, a manually operable member connected with said shifter and rotatably mounted on the motor casing, said member having a spiral 125 slot, and a stationary pin extending into said slot for causing said member when turned to move said shifter endwise.

2. In combination in a fluid actuated motor, reciprocating valves for controlling the 130

admission and exhaust of motive fluid to and from the power cylinders of the motor, a hollow shaft, an eccentric surrounding said hollow shaft and rotated thereby, said eccentric being connected with said valves for operating the same, a gear pinion in said hollow shaft, an eccentric shifter slidably mounted in said hollow shaft and having a bifurcated end provided with rack teeth in mesh with said pinion, a block extending across said hollow shaft through the bifurcated end of said shifter and having rack teeth in mesh with said pinion, said block having its ends extending beyond said hollow shaft through slots therein for supporting said eccentric, and actuating means for said shifter.

3. In combination in a fluid actuated motor, valves for controlling the admission and exhaust of motive fluid to and from the cylinders of said motor, an eccentric for operating said valves, a self closing starting valve controlling the supply of motive fluid to the cylinders through the first mentioned valves, an operating member rotatably mounted on the motor casing and having a spiral slot with straight ends, and a fixed pin extending into said slot to shift the eccentric when carried through the spiral portion of said slot and permit the opening of the starting valve as the pin enters the straight portions of said slot.

4. In combination in a fluid actuated motor, valves for controlling the admission of motive fluid to the cylinders of the motor, an eccentric for operating said valves, a self closing starting valve for controlling the supply of motive fluid to said cylinders through said first mentioned valves, a trigger for opening said starting valve, an operating member rotatably mounted on the motor casing and having side arms, means connecting said member with said eccentric for shifting the eccentric upon pulling downward on said arms, and means connecting said member with said trigger for opening the starting valve upon pulling downward on either of said arms after the eccentric has been completely shifted.

5. In combination in a fluid actuated motor, valves for controlling the admission of motive fluid to the cylinders of said motor,

an eccentric for operating said valves, a shifter for said eccentric, a bushing rotatably mounted on the motor casing and having a spiral slot, a pin fixed to the motor casing and extending into said slot, an actuating member secured to said bushing, a disc loosely mounted on said shifter and clamped between said member and bushing, and two collars keyed to said shifter on opposite sides of said disc and bearing against the same.

6. In combination in a fluid actuated motor, valves for controlling the admission and exhaust of motive fluid to and from the cylinders of said motor, an eccentric for operating said valves, a self closing starting valve for controlling the supply of motive fluid to said cylinders through said first mentioned valves, a trigger pivoted to the motor casing for opening said starting valve, a manually operable member rotatably mounted on a fixed part of the motor casing and connected with said eccentric for shifting the same, and a rod extending between said member and said trigger and having pivotal connection with both for operating said trigger to open said starting valve upon the turning of said member.

7. In combination in a fluid actuated motor, valves for controlling the admission and exhaust of motive fluid to and from the cylinders of said motor, an eccentric for operating said valves, a self closing starting valve for controlling the supply of motive fluid to said cylinders through said first named valves, a manually operable member mounted on a fixed part of said casing and connected with said eccentric for shifting the same, a pivoted trigger on the motor casing above said member, a rod extending between said trigger and said member and having pivotal connection with both for opening the starting valve through the trigger on pulling the rod downward by turning said member, and spring means acting on said trigger to return said rod to vertical position aligned with said trigger and said member upon releasing said member.

In testimony that I claim the foregoing as my invention. I affix my signature, this 26th day of October, A. D. 1921.

REINHOLD A. NORLING.
